UNITED STATES PATENT OFFICE.

FLORA E. JOUSSET, OF NEW YORK, N. Y.

VEHICLE-GUARD.

No. 826,432.

Specification of Letters Patent.

Patented July 17, 1906.

Application filed April 4, 1906. Serial No. 309,800.

To all whom it may concern:

Be it known that I, FLORA E. JOUSSET, a citizen of the United States, residing at New York, in the county of New York and State of New York, have invented new and useful Improvements in Vehicle-Guards, of which the following is a specification.

My invention relates to vehicle-guards, and is adapted to fit around the body and 10 wheels of a vehicle in proximity with the ground, so that objects which may lie in the path of a wagon or car may be deflected and thrown aside, so that a vehicle is relieved from danger of damage and pedestrians or 15 people walking in the path of the wagon or car are not exposed to the danger of being run over.

These and other objects of my invention are more fully described in the following 20 specification and pointed out in the appended claims.

In the drawings forming a part of this application and accompanying same like reference characters are used to designate the 25 same parts in the various figures.

Figure 1 is a side elevation of an automobile provided with my improved guard. Fig. 2 is a side elevation of a street-car also provided with a guard. Fig. 3 is a detail view 30 of a portion of the guard. Fig. 4 represents the means adopted to connect the guards on a train of cars, so as to make the said guard continuous.

In providing an automobile with this improved guard a rod 5 is arranged around the car, including its wheels, and hung from the body of the car by means of the brackets 6' or similar means, and on this rod 5 is hung a guard 6, which has its lower end connected to 40 a rod and which is made of collapsible material, such as metal links strung together, as shown in detail in Fig. 3, where it will be seen that the links 7 are provided with eyes 8 which engage each other. At certain points 45 along the length of the guard it is divided and is adapted to be shoved aside upon the rods, so that access may be had to the machinery below the car. These sections of the guard may be hooked together again by 50 means of any suitable device and the guard again given the appearance of being one continuous piece. In the use of the guard on an automobile it is obvious that I may confine myself to the use of canvas or other stout 55 fabric, which will not only protect people

who might be thrown down in the path of the automobile, but will also serve to prevent the spread of dust and dirt by the vehicle as it passes at a rapid rate of speed. The circulation of air which results from rapid motion 60 would in this case be confined to a small area, and consequently its effect upon the dust of the road would be reduced to a minimum. In applying this device to a street-car, as shown in Fig. 2, the car is also provided with 65 a rod 5, which is arranged around the body and platform, and this curtain of wirework or similar material is hung thereon and is adapted at certain points to permit of access to machinery beneath the car and is hooked 70 together, as above described. It is evident that such a guard as this may be used on a train of cars and the guard of each car connected with the adjacent car by means of a short section of the material, so that the 75 whole train may be provided with the guard, so as to protect people or animals from death by being thrown or drawn under the train.

Various modifications may suggest themselves in the use of this device without departing from the broad idea of a guard to fit around the frame of a vehicle.

At the front end of vehicles the guard may be formed into a point or angle, as at 6², in order to give the same a symmetrical appearance and be more effectual in pushing people or objects aside in case they happen to be in the road of the wagon or car.

In Fig. 4 I have shown the means of connecting the ends of the guards of two separate cars, and in this case I use a collapsing frame 9, similar to the ordinary folding gates employed as entrances to the platforms of cars, and this connection allows a contraction or expansion of the space between the 95 two cars, so that a complete shield is afforded along the whole length of a train.

Having thus described the invention, what I claim as new is—

1. In a guard for vehicles, the combination of a rod adapted to be attached to the vehicle, of a curtain adapted to be carried with the rod and slid upon same.
2. In a guard for vehicles, the combination with a rod carried by the vehicle, of two or more curtains made of flexible material and adapted to be separated or drawn and held together.
3. In a guard for vehicles, the combination with two or more curtains made of flexi-

ble material adapted to be suspended from the vehicle and flexible connections joining the two adjacent ends of the curtain, which may be attached to connected vehicles so that the space between the vehicles may be increased or decreased while the curtain remains substantially one continuous piece.

In testimony whereof I affix my signature in presence of two witnesses.

FLORA E. JOUSSET.
